UNITED STATES PATENT OFFICE.

FRANK C. H. STRASBURGER, OF CHICAGO, ILLINOIS, ASSIGNOR TO WILLIAM HORLICK, JR., OF RACINE, WISCONSIN.

DISPENSER.

1,282,310.

Specification of Letters Patent. Patented Oct. 22, 1918.

Application filed April 23, 1917. Serial No. 163,862.

To all whom it may concern:

Be it known that I, FRANK C. H. STRASBURGER, a citizen of the United States, residing at Chicago, in the county of Cook and 5 State of Illinois, have invented certain new and useful Improvements in Dispensers, of which the following is a specification.

This invention relates to a dispenser for malted milk and material of a similar character and has for its object the provision of 10 readily operable means for delivering accurately measured quantities of the malted milk or other material from a storage receptacle containing a supply thereof.

15 A further object of my invention is the provision of a dispenser adapted for use in connection with the receptacles in which the malted milk or other material is commercially packed and sold, thus avoiding the 20 necessity of transferring the material to a special container.

Further objects of my invention are the provision of means for breaking up lumps of the material both in the receptacle and in 25 the measuring chamber, means whereby the interior of the measuring chamber is visible previous to the discharge of the material therefrom, means for varying the capacity of the measuring chamber and in general to 30 provide a device which may be maintained in a sanitary condition and which will hold a supply of the material protecting it from contamination and deliver measured quantities of the material as needed with a minimum 35 expenditure of time and effort.

Further objects and advantages of my invention will be apparent as it is better understood by reference to the following specification when read in connection with the 40 accompanying drawing, illustrating the preferred embodiment thereof, in which—

Fig. 1 is a view in perspective of a dispenser according to my invention;

Fig. 2 is a vertical section through a portion of the device illustrating in detail the means for supporting the receptacle;

Fig. 3 is a detail in perspective of the measuring chamber;

Fig. 4 is a vertical section through the 50 complete dispenser;

Fig. 5 is a section on the line 5—5 of Fig. 4; and

Fig. 6 is a section on the line 6—6 of Fig. 4.

55 Referring to the drawing, 5 indicates a base which is preferably constructed of

some heavy material to make the structure stable. A pedestal 6, flanged at 7, is secured to the base 5 by screws 8 passing through the flange. A block 9 is secured within the 60 upper end of the pedestal 6 and supports a pivot screw 10 on which the clamping arms 11 and 12 are mounted. The arms 11 and 12 are provided at their lower edges with inwardly directed supporting flanges 13 and a 65 ring 14 of rubber or other resilient material is arranged on the inner faces of the arms 11 above the flanges 13 to engage the cap 15 threadedly mounted on the receptacle 16. At their forward ends the arms 11 and 12 70 are provided with extensions 17 and 18. A yoke 19 is pivotally mounted at 20 on the extension 17 and is provided with a locking finger 20' pivotally mounted at 21 thereon, the inner end of which engages a notch 22 75 in the extension 18. When the yoke and locking finger are disposed as indicated in Fig. 5 of the drawing the arms 11 and 12 are securely locked in position to hold the receptacle 16 in inverted position so that the 80 contents will readily flow therefrom.

The receptacle 16 is an ordinary glass bottle in which malted milk is commercially packed and sold and when the contents is exhausted a filled bottle is substituted therefor. The cap 15 is identical with the metal cap now commonly employed to seal the bottles except that the central part is cut away to permit the contents of the bottle to 90 flow therefrom when assembled with the dispenser and inverted.

The mechanism for measuring and delivering quantities of material from the receptacle 16 comprises a shell 23 to which the cap 15 is clamped by a flanged collar 95 24 threadedly engaging the shell. The shell 23 receives the material through an inlet 25 and delivers it through an outlet 26. Midway between the inlet and outlet the shell is provided with a cylindrical bearing to 100 support the measuring chamber 27 having an opening 28 in one side thereof to receive the material from the inlet 25. One end of the measuring chamber 27 is permanently closed by an integral head 29 provided with an operating member 30 whereby the chamber may be rotated until the opening 28 is 105 opposite the outlet 26, thus permitting the discharge of the material contained within the chamber. The shell 23 is provided adjacent the cylindrical bearing with a slot 31 to receive two pins 32 on the head 29 110

which limit rotation of the measuring chamber by engagement with a pin 33 fixed in the slot 31. The opposite end of the measuring chamber 27 is provided with a threaded cap 34. By rotating the cap it may be adjusted relative to the head 29 to vary the capacity of the measuring chamber. Removal of the measuring chamber is normally prevented by a screw 34' mounted in the shell 23 and engaging a slot 35' in the outer surface of the measuring chamber. The cylindrical bearing portion of the shell 23 is provided with an opening 35 having a seat to receive a transparent window 36 of celluloid or glass which permits the interior of the measuring chamber to be seen by the operator before the measuring chamber has been rotated to its discharging position. Thus if for any reason the measuring chamber is not properly filled it may be returned to again register the opening 28 with the inlet permitting a further supply of material to flow into the chamber.

In order to maintain the material in a loose condition in which it will readily flow from the receptacle 16 I provide a rod 37 rotatably and vertically movable in a suitable bearing 38 in the shell 23. At its upper end the rod 37 is provided with an opening to receive a flexible scraper 39 which is held in position by a nut 40. The scraper is sufficiently flexible to permit it to be drawn downwardly from the position indicated in Fig. 4 into the mouth of the receptacle 16 and in either position it may be rotated by means of a knurled head 41 on the lower end of the rod 37. I also provide a stirrer within the measuring chamber comprising a rod 42 having bearings in the head 29 and cap 34 and being provided with a knurled head 43. Within the measuring chamber the rod 42 is provided with stirring arms 44 which, when the rod is rotated, break up any lumps of the material permitting the chamber to be completely filled. The base 5 may be provided with an upwardly-directed flange or lip 45 directly under the outlet 26 to position the glass or other receiver into which the material is delivered by the dispenser.

The mode of operation of my invention will be readily understood from the following brief description thereof. The shell 23 with the cap 15 secured thereto is released from the clamping arms 11 and 12 and the cap 15 is substituted for the usual cap on the filled receptacle 16. In assembling the cap 15 with the receptacle 16 the scraper 39 is sprung sufficiently to permit it to pass through the neck of the receptacle. The receptacle is then inverted and the arms 11 and 12 are clamped about the cap as indicated in the drawing. The rubber ring 14 not only assists in securing the receptacle

in position but prevents possible breakage by the exertion of too much pressure on the neck of the bottle. The parts being assembled the operator grasps the operating member 30 and rotates the measuring chamber until the opening 28 registers with the inlet 24. If the material fails to flow freely from the receptacle the rods 37 and 42 may be operated to break up any lumps. The measuring chamber is then rotated to carry the opening 28 in a clockwise direction past the window 36 so that the operator may ascertain whether the chamber is properly filled. If not the chamber may be returned to its former position and the material further agitated by operating the rods 37 and 42. This, however, is rarely necessary. If the chamber is properly filled rotation is continued in the same direction until the opening registers with the outlet 26 when the material will automatically flow to any suitable receiver disposed therebeneath. The capacity of the measuring chamber may be varied by rotating the cap 34 moving it toward or from the head 29.

From the foregoing it will be appreciated that I have perfected a dispenser of simple construction, the parts being readily separable for cleaning when necessary which will maintain a supply of material such as malted milk, preventing contamination thereof, and which will deliver measured quantities of the material as required. My device maintains the material in a sanitary condition and prevents waste thereof. As compared with the present method of dispensing malted milk from an open receptacle with a spoon my device presents marked advantages which should appeal to persons vending or using malted milk as a beverage.

I claim:

1. A dispenser for pulverulent or granular material comprising a receptacle for the material, means for supporting said receptacle in inverted position, a hollow shell communicating with the mouth of said receptacle and provided with an outlet, rotatable means providing a chamber above said outlet to receive a quantity of the material, means for rotating said rotatable means to discharge the contents thereof and means axially arranged within said chamber and adapted when actuated to agitate the material therein.

2. A dispenser for pulverulent or granular material comprising a receptacle for the material, means for supporting said receptacle in inverted position, a hollow shell communicating with the mouth of said receptacle and provided with an outlet, rotatable means providing a chamber above said outlet to receive a quantity of the material, means for rotating said rotatable means to discharge the contents thereof, a shaft

extending axially through said chamber, and agitating means on said shaft within said chamber.

3. A dispenser for pulverulent or granular material comprising a receptacle for the material, means for supporting said receptacle in inverted position, a hollow shell having an inlet communicating with the mouth of said receptacle and an outlet, a hollow cylindrical member mounted to rotate in said shell and having an opening in one side, means for rotating said member to cause said opening to selectively register with the inlet to or outlet from said shell, a shaft extending axially through said cylindrical member, and agitating arms on said shaft within said member.

4. A dispenser for pulverulent or granular material comprising a receptacle for the material, means for supporting said receptacle in inverted position, a hollow shell having an inlet communicating with the mouth of said receptacle and an outlet, a hollow cylindrical member mounted to rotate in said shell and having an opening in one side, means for rotating said member to cause said opening to selectively register with the inlet to or outlet from said shell, and agitating means in said cylindrical member, including an axially disposed shaft and agitating arms supported thereon.

5. A dispenser for pulverulent or granular material comprising a receptacle for the material, means for supporting said receptacle in inverted position, a shell communicating with the mouth of said receptacle, means on said shell providing a chamber to receive a quantity of the material, means for discharging the material therefrom, agitating means in said chamber, and independently operable agitating means in said receptacle to insure delivery of the contents thereof.

6. In a dispenser for pulverulent or granular material the combination of a recep-

tacle for the material, means for supporting said receptacle in inverted position, a hollow shell having an inlet communicating with the mouth of said receptacle, and provided with an outlet, a hollow cylindrical member having an opening in its cylindrical wall, rotatably mounted in said shell, means for rotating said cylindrical member and agitating means therein and extending axially thereof.

7. In a dispenser for pulverulent or granular material the combination of a receptacle for the material, means for supporting said receptacle in inverted position, a hollow shell having an inlet communicating with the mouth of said receptacle, and provided with an outlet, a hollow cylindrical member having an opening in its cylindrical wall, rotatably mounted in said shell, means for rotating said cylindrical member, agitating means therein and extending axially thereof, and a window in said shell between the inlet thereto and outlet therefrom permitting observation of the contents of said cylindrical member as the latter is rotated.

8. In a dispenser for pulverulent or granular material, the combination of a receptacle for the material, means for supporting said receptacle in inverted position, a hollow shell having an inlet communicating with the mouth of said receptacle and provided with an outlet, a hollow cylindrical member having an opening in its cylindrical wall rotatably mounted in said shell, means for rotating said cylindrical member, an adjustable cap in the end of said cylindrical member, and agitating means in said cylindrical member and extending axially thereof.
